UNITED STATES PATENT OFFICE

152,981

DESIGN FOR A GIRDLE

Ethel R. Kaupp, New York, N. Y.

Application July 2, 1947, Serial No. 140,063

Term of patent 14 years

(Cl. D20—2)

To all whom it may concern:

Be it known that I, Ethel R. Kaupp, a citizen of the United States and residing at New York, in the county and State of New York, have invented a new, original, and ornamental Design for a Girdle, of which the following is a specification, reference being had to the accompanying drawings, forming part thereof and in which

Fig. 1 is a front perspective view of a girdle, showing my new design,

Fig. 2 is a rear perspective view of the same.

The characteristic feature of my design resides in the combination on the girdle disclosed of the specific waistband or top cuff which flares outwardly above the waistline, and terminates in a point in the front portion below the waistline, in association with a vertically divided, shaped front panel section between the side seams and an undivided, shaped rear panel section, all as shown.

I claim:

The ornamental design for a girdle, substantially as shown and described.

ETHEL R. KAUPP.
